CLAIM

The ornamental design for a rotary seat, as shown and described.

DESCRIPTION

FIG. 1 is a front, right, top perspective view of a rotary seat showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 of FIG. 1; and,

FIG. 9 is an enlarged view of the encircled area 9 of FIG. 2. The broken lines shown on the drawings depict portions of the rotary seat that form no part of the claimed design. The dot-dash lines denote the enlarged views, and form no part of the claimed design.
